US0D1035667S

(12) **United States Design Patent** (10) **Patent No.:** **US D1,035,667 S**
(45) **Date of Patent:** **** Jul. 16, 2024**

(54) **DOCKING STATION**

(71) Applicant: **SHENZHEN ORICO TECHNOLOGIES CO., LTD.**,
Shenzhen (CN)

(72) Inventors: **Yeyou Xu**, Shenzhen (CN); **Chuanxin Mao**, Shenzhen (CN)

(73) Assignee: **SHENZHEN ORICO TECHNOLOGIES CO., LTD.**,
Shenzhen (CN)

(**) Term: **15 Years**

(21) Appl. No.: **29/872,278**

(22) Filed: **Mar. 9, 2023**

(30) **Foreign Application Priority Data**

Dec. 8, 2022 (CN) 202230822532.9

(57) **CLAIM**

The ornamental design for a docking station, as shown and described.

DESCRIPTION

FIG. 1 is a front, right and bottom perspective view of a docking station showing our new design;

FIG. 2 is a front, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a partial enlarged view taken from circle 9 in FIG. 2.

The dash-dash broken lines in the drawings depict the portions of the docking station which form no part of the claimed design.

The dot-dash broken lines in the drawings depict the boundaries of the partial enlarged views that form no part of the claimed design.

1 Claim, 9 Drawing Sheets
